UNITED STATES PATENT OFFICE

JOE S. MCKIBBON, OF COLUMBIA, TENNESSEE

WRENCH

Application filed February 16, 1929. Serial No. 340,604.

This invention relates to wrenches, and more particularly to adjustable wrenches, adapted to satisfactorily operate upon bolts, nuts, pipes, or the like of varying sizes.

5 It is a major purpose of the present invention to provide a novel adjustable wrench including a stationary jaw and a movable jaw associated therewith, the movable jaw being adapted when operating upon a nut, pipe, or 10 the like, to automatically assume an advanced position with respect to the stationary jaw, whereby the jaws are adapted to securely clamp upon the nut or the like thus preventing any possibility of the wrench slipping 15 upon the same.

It is a further object of the present invention to provide a novel wrench of the class set forth including a stationary jaw and a movable jaw, wherein all the adjustable and movable parts are entirely enclosed whereby no grease, dirt or the like can enter therein thus to interfere with the adjustment or operation of the wrench.

20 It is a further object of the invention to provide a novel adjustable wrench of the class set forth which will operate as satisfactorily upon substantially round surfaces such as pipes, bolts or the like, as upon bolts, nut-heads, etc.

25 It is a still further object of the invention to provide a novel wrench of the class set forth which may be readily and conveniently adjusted and operated, which will be highly efficient, which will be extremely attractive in 30 appearance, and which may be economically manufactured. Further objects of the invention will be hereinafter more fully set forth.

35 The accompanying drawings illustrate one 40 practical wrench embodying the invention which will be described in detail to enable others to understand and use the same, but the invention is not considered restricted to the specific construction shown in the drawings, and reference is therefore had to the 45 claims for summaries of the essentials of the invention and of the novel features of construction and of the novel combinations of parts for all of which protection is desired.

50 In the drawings:

Figure 1 is a view in side elevation of one form of wrench constructed in accordance with the present invention.

Figure 2 is a view in side elevation similar to Figure 1, the rolling hinge being illustrated 55 in section.

Figure 3 is a view in side elevation of the jaws of the wrench, parts being broken away to illustrate the adjusting spindle, the movable jaw of the wrench being shown in advanced and operative position.

Figure 4 is a detail perspective view of the connecting rolling hinge detached.

Figure 5 is a detail perspective view of the 60 adjusting spindle detached.

Figure 6 is a view in side elevation of one of the adjusting screws upon which the adjusting spindle operates.

As shown in the drawings, in which similar 70 reference characters refer to similar parts, the novel wrench which may be of any desired size, includes a stationary jaw 1, preferably forming an integral part of the handle 2, and a movable jaw 3; both of the jaws being 75 provided on their inner opposed faces with notches or serrations as is well known in the art, to assist in the secure gripping of the nut, bolt, pipe or the like. The stationary jaw—which is the upper jaw—is provided on the bottom surface thereof, and adjacent the handle proper, with an angularly disposed cut away portion or recess 4 which includes a shoulder 5 at the front end thereof and which terminates at the rear thereof in a substantially hook-like member 6. The jaw 1 is 80 further provided on the upper surface thereof with a notch or recess 7 providing a seat for the fulcrum of the rolling hinge 12 85 as will be hereinafter more fully described.

The bottom and movable jaw 3 is provided 90 with an enlarged extremity 8 including an angularly directed shoulder 9 and a hook-like recess 10, it being noted that the jaw 3 is complementarily conformed with respect to the recess in the jaw 1, whereby in the inoperative position of the wrench, as illustrated in Figure 2 of the drawings, the shoulder 9 will engage with the shoulder 5 preventing further forward movement of the jaw 3 with 95 respect to the jaw 1.

In like manner in the operative position of the wrench, as more particularly illustrated in Figure 3 of the drawings, with the movable jaw in advanced position the hook-like portion 6 will engage within the recess 10 and the extremity 8 of the jaw 3 will be securely held and seated in the recess 4, thus limiting the movement of the jaw 3 within the recess 4 and securely retaining the said jaw in operative position. The jaw 3 is further provided on the bottom surface with a recess or seat 11, similar to the recess 7 and oppositely directed with respect thereto, adapted for engagement with a pin or the like upon 15 the rolling hinge 12.

Any desired means might be provided for urging and maintaining the jaw 3 in inoperative and retracted position. Preferably such means comprises a coil spring 13 having one extremity thereof housed within a recess 14 formed within the extremity 8 of the jaw 3, the opposed extremity of the spring being adapted to be seated within a notch 15 formed within the recess 4 in the stationary jaw 1. Obviously the spring 13 will tend to urge the bottom movable jaw into inoperative position, the construction being such that when the jaws of the wrench are in engaged position the spring 13 will be compressed within 30 in the recess 14.

A connecting member or rolling hinge 12 is provided for maintaining the jaws in assembled relationship with the extremity 8 of the movable jaw within the recess 4 in 35 the stationary jaw.

Preferably the hinge 12 is so conformed as to completely surround the entire connection between the two jaws, thus enclosing or housing the same and preventing any possibility of the fouling thereof through grease, dirt or the like and the resultant impairment of the operation of the wrench. As illustrated more particularly in Figure 4 of the drawings, the rolling hinge 12 preferably 40 comprises a pair of relatively flat opposed plates 16 substantially circular in peripheral conformation and maintained spaced by a pair of oppositely disposed hinge pins 17 and 18; the hinge pin 18 forming an integral 45 part of an arcuate peripheral wall 19. The hinge pin 17 is adapted to engage within the recess or seat 7 provided in the stationary upper jaw, while the hinge pin 18 is adapted in like manner for engagement with 50 the recess or seat in the movable jaw.

It will be noted that when the jaws of the wrench are in inoperative position, see Figure 2 of the drawings, the arcuate wall 19 will serve to close the space between the hook-like member 6 of the stationary jaw and the recess 10 of the movable jaw. Obviously when the wrench is engaged with some object, as a bolt, nut, pipe or the like, and the movable jaw is advanced to the position illustrated in Figure 3 of the drawings, the hinge 55

12 will pivot into proper position upon its fulcrum or hinge pin 17.

In the advancement of the movable jaw from the position illustrated in Figure 2 to the position illustrated in Figure 3 of the drawings, the extremity 8 of the jaw 3 rides upon the angularly disposed upper wall of the recess 4 in the jaw 1 until the jaw 3 reaches the limit of its movement where it is securely seated and held in position, the hook-like portion 6 engaging the recess 10 and the extremity 8 snugly fitting the complementarily conformed portion of the recess 4. In like manner when the bottom jaw 3 returns to inoperative position the extremity 8 thereof rides the upper wall of the recess 4 until the shoulder 9 engages the shoulder 5.

Suitable means are provided for adjusting the jaws to fit nuts, pipes, bolts or the like of varying sizes. Preferably such means comprises an adjusting sleeve 20 interiorly screw-threaded for engagement with a pair of adjusting screws properly seated within the jaws 1 and 3. Each of the jaws 1 and 3 is provided with a tapered bore 23 through which the adjusting screw 21 depends, and a slightly reduced seat 24 adapted to receive the preferably oval head 22 of the adjusting screw 21, a shoulder 25 being provided between the bore 23 and the seat 24 to prevent the passing of the head of the screw therethrough. Each seat 24 is provided with a pair of opposed slots 24a adapted to receive therein lugs or the like 22a integrally formed upon the heads of the adjusting screws 21 thus preventing any rotation of the screw within the jaw in which it is mounted.

Closure members 26 are preferably provided to securely close the seats 24 after the screws have been positioned therein, thus preventing any dirt, grease or the like entering into the seat. These closures may be fastened in position by any desired means as by welding or the like.

The adjusting screws are oppositely screw-threaded and in like manner the adjusting sleeve is similarly interiorly screw-threaded whereby rotation of the spindle will operate upon both screws and upon both jaws simultaneously to open or to close the same to properly adjust the wrench. Preferably the sleeve 20 is provided adjacent the center thereof with a knurled thumb nut 27 to assist in the rotation thereof; the adjacent portions of the jaws 1 and 3 being cut away as at 28 to assist in a more convenient operation or rotation of the thumb nut and to permit the same to be of a size so as not to overlie the face walls of the jaws of the wrench.

To normally maintain the jaws in expanded position and thus assist in the ready operation of the adjusting sleeve, a leaf spring 29 is interposed between the jaws 1 and 3 and has one extremity thereof secured to the jaw 1 as at 30. Preferably the other extremity of the 125

spring is free and engages against the jaw 3 and urges the said jaw away from the upper jaw of the wrench.

The opposed engaging surfaces of the jaws it will be noted are provided with two sets of operative surfaces, 31 and 32. The surfaces 31 are very slightly serrated and are adapted to operate upon nuts, bolt-heads and the like, being disposed in substantially parallel relationship. The surfaces 32 are slightly angularly disposed and are toothed, being adapted to operate upon pipes, bolts, or other round surfaces.

In the operation of the wrench as first upon a nut or the like, the adjusting sleeve is first rotated to space the jaws 1 and 3 the required distance apart, whereupon the wrench is applied in the usual manner. The applying of pressure upon the handle of the wrench will then result in the advancing of the bottom movable jaw within the recess 4 until the jaws are securely clamped upon the nut and the same may then be readily removed from the bolt or the like upon which it may be mounted. It will be noted that the operative surfaces 31 remain at all times in parallel relationship even during movement of the jaw 3 relative to the jaw 1, thus no damage or scarring may be done to the nut during the manipulation thereof by the wrench. During the advancement of the jaw 3 the adjusting spindle and screws assume a slight change in angularity to compensate for the relative movement between the jaws. During this advancement or movement of the bottom movable jaw 3, the opposed operative surfaces 31 are brought closer together through the riding of the extremity 8 of the jaw 3 upon the upper wall of the recess 4 in the jaw 1, thus assisting in the clamping of the jaws upon the nut, pipe, or the like.

With the bottom movable jaw in the above described advanced position, it will be clear that it co-operates with the upper stationary jaw positively preventing disengagement or movement of the jaws with respect to each other and further with respect to the nut, any possibility of the wrench slipping from the nut thus being prevented. It will be obvious that the secure gripping is due to the operating surfaces of the jaws being at all times in parallelism so that both surfaces grip the faces of the nut with uniform pressure throughout the length of the said surfaces. The operation of the wrench as upon a pipe or the like is similar except that the toothed surfaces 32 are employed rather than the surfaces 31.

It is understood that this invention includes wrenches having differently shaped jaws, such as a form for nuts and a form for pipes as well as the combination type of jaw shown.

The invention having thus been described, what is claimed is:—

1. A wrench having a longitudinal extension or fixed jaw, a movable jaw extending longitudinally of the fixed jaw and the two having opposed co-acting jaw faces longitudinally thereof, means for connecting the movable jaw to the fixed jaw so that it may move longitudinally and so that such longitudinal movement varies the space between the jaw faces, one of said jaws having a recess to receive one end of the other jaw and forming a shoulder or stop at each end of the recess, the other jaw having a head engaging said recess and having stop shoulders to engage those of the recess and limit the longitudinal motion of the jaw, the floor of the recess being so inclined that the head moves outward as the movable jaw is caused to close by the longitudinal movement thereof. 70

2. A wrench having a longitudinal extension or fixed jaw, a movable jaw extending longitudinally of the fixed jaw and the two having opposed co-acting jaw faces longitudinally thereof, means for connecting the movable jaw to the fixed jaw so that it may move longitudinally and so that such longitudinal movement varies the space between the jaw faces, one of said jaws having a recess to receive one end of the other jaw and forming a shoulder or stop at each end of the recess, the other jaw having a head engaging said recess and having stop shoulders to engage those of the recess and limit the longitudinal motion of the jaw, the floor of the recess being so inclined that the head moves outward as the movable jaw is caused to close by the longitudinal movement thereof, the connecting means being adjustable to initially space the jaws. 85

3. A wrench having a longitudinal extension or fixed jaw, a movable jaw extending longitudinally of the fixed jaw and the two having opposed co-acting jaw faces longitudinally thereof, pivotal link means for connecting the movable jaw to the fixed jaw so that it may move longitudinally and so that such longitudinal movement varies the space between the jaw faces, one of said jaws having a recess to receive one end of the other jaw and forming a shoulder or stop at each end of the recess, the other jaw having a head engaging said recess and having stop shoulders to engage those of the recess and limit the longitudinal motion of the jaw, the floor of the recess being so inclined that the head moves outward as the movable jaw is caused to close by the longitudinal movement thereof, the stop shoulders of the head and recess preventing the link means from moving in one direction past that position in which the jaws are widest open. 105

In testimony whereof he affixes his signature.
